UNITED STATES PATENT OFFICE

WILLIAM HANSON, OF TRENTON JUNCTION, NEW JERSEY

INCUBATOR

Application filed December 21, 1928. Serial No. 327,656.

This invention relates to an improved cabinet incubator, and has more specific reference to the internal construction of the incubator, and associated elements which co-operate in producing a novel heating system for more efficient results.

Briefly described, the improved structure comprises a cabinet having insulated walls and suitably arranged ventilators. This 10 cabinet is provided at its interior with horizontal longitudinally extending partitions disposed in spaced parallelism and defining a central air shaft and side compartments.

A source of heat is associated with the 15 air shaft and this is in communication with its top and bottom and the side compartments. The side compartments are constructed to accommodate the tiers for rack supporting trays utilized as egg containers 20 and hatching drawers.

The principal novelty is predicated upon the system of heating including a natural draft circulation, whereby the heat will continue to circulate through the central shaft 25 and over the top of the partition, and down through the egg compartments, in order that the temperature of these compartments will be uniform from top to bottom at all times. A further feature of the invention is based 30 upon the utilization of electric heaters associated with a register located at the bottom of the central air shaft, as well as the employment of automatic thermostatic switches for regulating the heaters.

35 It follows that the outstanding object of the invention is to generally improve upon incubators of this class by providing one which is characterized by a novel arrangement of parts so cooperating and associated 40 as to better fulfill the requirements of an invention of this class and to produce stronger and better chicks.

Other features and advantages of the invention will become more readily apparent 45 from the following description and drawings.

In the drawings:

Figure 1 is a vertical sectional view 50 through a cabinet incubator constructed in accordance with the present invention,

Figure 2 is a horizontal sectional view through the same.

Figure 3 is a view in section end elevation showing the thermostatic switch control means,

Figure 4 is a longitudinal sectional view through Figure 3,

Figure 5 is a wiring diagram.

The enclosure comprises a cabinet of appropriate proportions including a suitable 60 floor 6, together with top, sides, and end walls.

The top and end walls are preferably made of inner and outer sections 7 and 8 spaced apart as shown to provide insulation spaces. 65 Likewise, the side walls are composed of spaced elements, the inner elements of which are in the form of removable or hingedly mounted glass panels or doors 9 and outer solid doors 10.

This arrangement permits proper access and frequent inspection in a convenient manner. As before indicated I provide a pair of spaced parallel partitions 11 on the interior. These are disposed longitudinally and have 75 their upper and lower edges terminating in spaced relation from the floor and ceiling respectively. These partitions define the central air shaft 12.

At one end of the air shaft is an outwardly 80 opening entrance door 13 permitting the attendant to enter the structure, if desired. Suitably supported between the lower portions of the partition is a grating 14 forming a register. Also supported beneath this register are electric heaters generally designated by the reference characters 15.

In actual practice it has been found advantageous to support a water filled tray or pan 16 on the register to moisten the upwardly 90 circulating heated air. The heaters as well as the registers, are supported in spaced relation above the floor.

The partitions also form a pair of duplicate egg compartments 17. In this connection it will be noted that extension floors 18 are formed upon the lower ends of the partition and extend into the compartments 17 to support racks, upon which the receptacles 95 are assembled in tiers.

100

For sake of distinction, the upper small trays are designated as egg pans 19, while the lower trays are hatching trays or drawers 20. In connection with these parts it is to be observed that they are accessible through the side closures 9 and 10 respectively. Moreover when the outer closures 10 are open, the trays can be inspected through the transparent glass panels or closures 9.

10 The air circulation can be regulated partially by the swingable valve plate 21 the same being suspended from the ceiling over the central portion of the air shaft 12. This can be swung from its central position to 15 either dotted line position seen in Figure 1 to shunt the air column to an opposite side if desired.

Formed in the roof or ceiling are air ventilating openings 22 having automatically operable closures 23. The closure in each instance is mounted on a weighted pivotally mounted lever 24 whose intermediate portion is connected by an operating link 25 with an expansible thermostat on the interior of the cabinet.

Associated with the thermostats 26 are switch controlling thermostats designated generally by the reference characters 27. The construction of the thermostat is shown in 30 Figures 3 and 4. It comprises a frame 28 carrying a plurality of double wafer thermostatic elements 29. These have adjustable connections with a slide 30 through the medium of an adjustable coupling 31. The slide 35 is mounted in a cross bar 32 on the frame and has a forked end, the arms of which straddle a pivotally mounted contact actuator 33.

This actuator carries a relatively movable contact 34 cooperating with a relatively stationary contact 35 on the rigid bracket 36. As shown in the wiring diagram 25, the plurality of electric heaters are included in the electric circuits controlled by the thermostatic static switches.

Hence, the circuit is turned off and on automatically according to the temperature conditions within the cabinet. In practice, a master control switch 37 may be provided 50 for throwing the heaters out of operation whenever desired.

It is yet to be mentioned that additional ventilators 38 may be provided in the cabinet, preferably near the bottom for introducing cold air at desired intervals.

The features to be emphasized are these. First, the method of circulation of air between the communicating air shafts and egg compartments, is essential to the efficient operation of the invention, since this maintains the desired uniform temperature for appropriate incubation.

A number of ventilators are provided and these work automatically. The heaters are 65 controlled by thermostatic switches which as

before stated also operate automatically and these thermostats can be regulated as desired. These and other features and advantages of the invention have doubtless been made apparent from the description and drawings.

Therefore, a more lengthy description is regarded unnecessary.

Minor changes in shape, size, and arrangement of parts may be resorted to in actual practice if desired.

Having thus described my invention, what I claim as new is:

1. An incubator cabinet comprising an enclosure provided with longitudinally extending spaced parallel partitions defining a central air circulating shaft through which air passes upwardly, and a pair of side compartments, said partitions having their upper and lower edges spaced respectively from the floor and ceiling of the enclosure, a horizontal register supported between the lower portions of said partitions, and the heating means located beneath said register, together with a swingably mounted valve plate suspended from the ceiling and located centrally over said air shaft and adapted to be swung against either partition to shunt the circulating air in a desired direction.

2. In a cabinet incubator of the class described, an enclosure, a pair of parallel spaced longitudinally extending vertically disposed partitions in said enclosure having their upper and lower edges terminating in spaced relation from the ceiling and floor respectively to simultaneously form a central air shaft and an egg compartment on a pair of opposed sides of the shaft, horizontal extensions carried at the lower end portion of said partitions and extending into said compartments and disposed in spaced relation to the floor, racks supported on said extensions and located in said compartments, a plurality of receptacles arranged in tiers on said racks, a register disposed between the lower end portions of said shaft, heating elements supported beneath said register, a swingably mounted centrally arranged valve plate extending from the ceiling and cooperable with said partitions for shunting the circulating air in the desired direction, and an entrance door at one end of said shaft.

In testimony whereof I affix my signature.

WILLIAM HANSON.
